H. C. PEDERSEN.

CIGARETTE CASE.

APPLICATION FILED MAR. 11, 1913.

1,081,512.

Patented Dec. 16, 1913.

UNITED STATES PATENT OFFICE.

HARALD C. PEDERSEN, OF NEW YORK, N. Y., ASSIGNOR TO THE FIRM OF AISENSTEIN & SCHILLER, OF NEW YORK, N. Y.

CIGARETTE-CASE.

1,081,512.

Specification of Letters Patent. Patented Dec. 16, 1913.

Application filed March 11, 1913. Serial No. 753,483.

To all whom it may concern:

Be it known that I, HARALD C. PEDERSEN, a subject of the King of Norway, and resident of the borough of the Bronx, city, 5 county, and State of New York, have invented certain new and useful Improvements in Cigarette-Cases, of which the following is a specification.

My present invention relates to a further 10 improvement or development of the cigarette case disclosed in Letters Patent of the United States No. 890,703, granted to me on June 16, 1908, and has for its object to simplify the construction of the case in such 15 a manner as to reduce the thickness of certain parts and to insure an easy and reliable operation.

A specific embodiment of my present invention will now be described in detail with 20 reference to the accompanying drawings, and the novel features will then be pointed out in the appended claims.

In the said drawings, Figure 1 is a vertical section on line 1—1 of Fig. 2, with the 25 case open; Fig. 2 is a face view of one of the lids and the cigarette holder proper, with the hinge eyes of the other lid in section; Figs. 3 and 4 are a top view and a bottom view respectively of the holder proper; 30 Fig. 5 is a perspective view of a shoe for centering the holder; Fig. 6 is a partial cross section taken on line 6—6 of Fig. 1; and Fig. 7 shows the holder proper released from one of the lids.

35 The case comprises the two lids or covers A, B pivoted together at one edge and adapted to be held in the closed position by a suitable catch C provided at the opposite edge. Each of the lids is made with hinge 40 sleeves or eyes A', B' adapted to receive a pintle D, which may be a torsional spring pintle of well-known character, having a tendency to open the lids when the catch C is released. The opening movement of the 45 lids is limited in any suitable way, as by having the adjacent edges of the lids abut against each other in the open position, as illustrated in Fig. 1.

I prefer to make the lids A, B with bezels, 50 or ribs A², B² extending practically continuously along the four edges of the lids A and B respectively (see Fig. 2), with short interruptions at the outer edges to receive the catch C, and with short interruptions at the inner edges (adjacent to the

hinge) to receive arms E' projected downwardly (or toward the hinge) from the cigarette holder proper E. The ends of the arms E' are formed with hinge-sleeves or eyes E² through which the pintle D extends, each eye E² being received between an eye A' of the lid A and the adjacent eye B' of the lid B. The holder E therefore swings on the same pivot as the lids A, B, but to a certain extent independently thereof, as will 60 be explained presently. The particular holder shown is adapted to contain ten cigarettes in a single row, but I do not restrict myself to this number of rows or cigarettes. The holder has a series of grooves 65 or seats E³ extending at right angles to the hinge axis and forming pockets for the individual cigarettes, which are held by means of a plate or wing F, pivoted to the holder at F', and pressed toward said holder 70 by springs G (Fig. 4). At the center of this holder E a stud E⁴ secured thereto rigidly, is projected downwardly, and this stud has a vertical slot E⁵ in which the central portion of a flat or leaf spring H is movable 75 up and down, the ends of said spring resting against the bottom of the holder E. Preferably, as shown in Fig. 4, the portion of the spring H received within the stud E⁴, is narrowed so as to prevent 80 endwise movement of the spring (lengthwise of the hinge axis). On this stud is adapted to slide the sleeve-like stem J' of a shoe J formed with inwardly turned edges J² which are adapted to embrace the 85 ribs A², B² adjacent to the hinge, the spring H being preferably fitted into lateral notches J³ of the stem J', so that the stem and shoe may not turn relatively to the 90 stud E⁴.

The holder E may be laid close against either one of the lids A or B when the case is opened but slightly, and the case may then be opened fully with the holder still adjacent to such one lid. This may be 100 found more convenient for inserting cigarettes in the holder. In this position, as shown in Fig. 7, the rib of one of the lids has swung beyond the inturned edge of the shoe J. Normally, however, the inturned edges of said shoe embrace the ribs of both lids, as shown in Fig. 1. In this case, said edges may also serve to limit the outward swinging of the lids. The main function of the shoe J however, is to keep the holder 110

E in a position central with respect to the lids, or midway between them, as the case is opened. This is due to the pressure exerted on said shoe by the spring H, which tends to keep the holder in a position bisecting the angle between the lids. If the holder is brought temporarily to one side, as shown in Fig. 7, then, upon closing the case entirely or almost so, the rib of the lid which was temporarily freed from the shoe J, will again be brought between the inturned edges of said shoe, and the holder will stand equi-distant from the lids as before. The passage of the lid from one position to the other will take place readily.

The device is simple and neat in appearance, lends itself readily to ornamentation, and on account of its thinness the case can be carried in a pocket conveniently.

20 By suitably changing the dimensions, the case may be adapted to hold cigars, matches, cards, etc., instead of cigarettes.

Various modifications may be made without departing from the nature of my invention as set forth in the appended claims.

I claim as my invention:

1. A case of the character described, comprising a pair of hinged lids forming a case, a holder secured to the hinge of the lids, a slotted stud secured to the bottom of the holder, a spring extending through the slot of the stud and bearing against the bottom of the holder, and a shoe fitted to slide on said stud and pressed by said spring against the lids adjacent to the hinge so as to nor-

mally keep the holder equidistant from the lids.

2. A case of the character described, comprising a pair of hinged lids forming a case, a holder secured to the case, a slotted stud secured to the bottom of the holder, a spring extending through the slot of said stud and bearing against the bottom of the holder, the portion of the spring which is within the stud being narrowed to prevent endwise movement of the spring, and a shoe fitted to slide on said stud and pressed by said spring against the lids adjacent to the hinge so as to normally keep the holder equidistant from the lids.

3. A case of the character described, comprising a pair of hinged lids forming a case, a holder secured to the hinge of the lids, a slotted stud extending from said holder toward the hinge, a spring extending through the slot of the stud and bearing against the holder, and a shoe notched to receive the spring and to prevent the shoe from turning relatively to the spring, said shoe being fitted to slide on the said stud and pressed by said spring against the lids adjacent to the hinge so as to normally keep the said holder equidistant from the lids.

In testimony whereof, I have hereunto affixed my signature in the presence of two subscribing witnesses.

HARALD C. PEDERSEN.
